UNITED STATES PATENT OFFICE.

JOSEPH A. GROEBLI, OF NEW YORK, N. Y.

SEWING MACHINE.

Application filed July 16, 1923. Serial No. 651,767.

To all whom it may concern:

Be it known that I, JOSEPH A. GROEBLI, a citizen of the United States, and a resident of the city, county, and State of New York, have invented certain new and useful Improvements in Sewing Machines, of which the following is a specification.

My invention relates to sewing machines, and its principal object is to obtain increased accuracy in the formation of loop stitches by snugging up the thread under the barb of the needle before the needle draws it down through the loop, my improvements being particularly directed to novel means whereby the slack of the thread is taken up at the proper moment, after which the normal tension of the thread is reestablished.

In the drawings I have illustrated my improvements as applied to a bead-sewing machine; and Fig. 1 is a side elevation of part of the head and attachments of a sewing machine provided with my improvements, the bead separator and looper being, however, in section; Fig. 2 is a top view, on an enlarged scale, of the thread reel and take-up mechanism, taken as on the line 2--2 of Fig. 1 looking down; Fig. 3 is an elevation of the reel holder and reel, taken as looking to the left on Fig. 2; Figs. 4, 5, and 6 are views illustrating successive positions of the take-up control as it revolves around its actuating cam; Figs. 7, 8 and 9 illustrate the positions of the threads and needle at the points in the formation of a stitch corresponding respectively with the positions of the mechanism illustrated in Figs. 4, 5, and 6; and Fig. 10 is a detail.

The same parts are designated by corresponding reference numerals in all the figures.

A type of machine to which my improvements may be applied is shown in my Letters Patent No. 1,445,764, of February 20, 1923; and the details of the embodiment of my improved mechanism in such a machine will be readily understood when it is noted that tubes 38 and 53 of my present application correspond to the elements similarly numbered in my aforesaid patent, and are supported and actuated in a similar manner; that similar needle actuating mechanism may be employed; and that the bead thread may be supplied by means like those illustrated in said patent.

In operation the needle 1 produces, with

the stitching thread 2, a loop stitch, the stitching thread being preferably thrown around the bead thread 3 by the looper 4, during the formation of the stitch, to attach that thread and its beads in proper position on the fabric. The looper 4 is carried by and revolves with the tube 38; while the bead separator shown is of the jawed type, and is adapted to release a bead with each revolution of the separator. The details of construction of this separator are the subject of a separate application, so I will not describe them further herein.

The stitching thread reel 6 is supported by and also revolves with the tube 38, being connected therewith by a suitable bracket 7, upon which it is mounted above a spring 8 and a ratchet wheel 9 to which it is connected by a pin 10. The reel turns on a spindle 11, being detachably held in place by a movable arm 14 carried by a shaft 15, the arm 14 being normally held down above the reel by a coiled spring 16, which permits it, however, to be raised and swung around sufficiently to clear the spindle 11 and the reel 6.

To the tube 53 is fastened a collar 20 provided with a cam race 21 on its lower side, against which travels the end of arm 22 fastened upon a shaft 23, which is rotatably mounted in a bearing on the bracket 12.

The arm 22 has an extension or branch 24, between which and the bracket 12 is stretched a spring 25, which normally keeps the end of the arm 22 in contact with the cam race 21.

A shaft 30 is journalled in the bracket 7, and is provided with a pawl arm 31 adapted to be thrown into and out of engagement with the ratchet wheel 9, and also with an arm 32, between which and a pin on the bracket 7 is stretched a spring 33 which tends to throw the pawl 31 into contact with the ratchet wheel 9. This movement of the pawl, however, is controlled through another arm 34, carried by the shaft 30, the free end 35 of which travels against the face of a cam collar 36, fastened, as by a set screw 37, to the shaft 53, and provided with a depressed portion 39 into which the end 35 of the arm 34 will enter, at each revolution of the bracket 7, so as to allow the pawl 31 to engage with the teeth of the wheel 9 and arrest the rotation of the reel.

This locking of the reel takes place, preferably, just before the end of the arm 22

reaches the recess in the cam collar 20; and the ratchet wheel is released from the pawl, preferably, just as the end of the arm 22 clears the recess in the cam race.

- 5 In operation, the stitching thread is drawn off its reel, under a normal tension, by the needle and the movement of the fabric, during the preliminary portion of the stitch forming cycle and until the needle is descending and the looper has swung around behind the needle, for instance, as indicated in Fig. 8. But, preferably, just before this position is reached the rotation of the tube 38 and the bracket 7 around the tube 53 10 brings the end 35 of the arm 34 to the recess 39 in the cam collar 36, allowing the spring 33 to rock the shaft 30, causing the pawl 31 to engage the ratchet wheel 9, stopping the rotation of the reel 6. 15 20 The continued rotation of the bracket 7 then brings the free end of the arm 22 to the recess in the collar 20, allowing the arm to rise, and to give a quick jerk upwards against the thread 2 which passes over the 25 arm on its course to the channel between tubes 38 and 58 through which it travels down to the looper and needle. The reel being held by the braking mechanism, embracing the ratchet wheel and pawl already described, 30 can not turn to yield more thread; and the slack of the thread between the reel and the fabric will be taken up by the upward movement of the arm 22, so as to draw the thread more or less taught and to snug 35 it around the shank of the needle 1 below its barb, preventing the barb from slipping past the thread and dropping the stitch. As the continuation of the stitch cycle requires more thread, this is provided for by the 40 gradual lowering of the arm 22 by the long slope of the cam race, as the arm travels past it, the thread meanwhile continuing to be carried around the needle under snug tension until the needle draws it down through the preceding loop, as illustrated in Fig. 45 9, when the arm 22 will ride out of the cam recess, leaving the arm 22 in its normal position.

Meantime the arm 34 has been passing
50 the recess in the cam collar 36, first braking
the reel 6 and then gradually releasing
the brake, until, preferably as the arm 22
clears the recess in cam collar 20, the arm
34 will clear the recess in collar 36, freeing
55 the reel 6 to yield the thread under normal
tension, until the take-up operation is re-
peated in the next stitch cycle.

60 Thus the tension on the thread is varied so as to correspond to the requirements of accurate work in the various phases of the stitch cycle, and an even and accurate output is secured from the machine with a minimum of defects from dropped stitches or other similar errors in the stitching.

65. The success of this arrangement lies, in

principle, in snubbing up the thread at the proper instant to insure its catching under the barb of the needle, and in then reestablishing the normal tension, as already explained.

The mechanism illustrated and described is selected as a typical example of the application of my invention, but not as an exclusive form of embodiment thereof. For it is obvious that details of construction may be modified, as by the use of mechanical equivalents or the like, without departing from the spirit of my invention or the scope of the claims. 75

Having thus described my invention, what I claim and desire to secure by Letters Patent of the United States, is:—

1. In a sewing machine, embodying loop stitch forming means including a barbed needle, the combination of rotatable thread carrying and supplying means, automatic means for temporarily and positively arresting and holding the thread carrying and supplying means once during each stitch cycle, so as to permit the release of the thread, and means for positively increasing the tension on the thread after the carrying and supplying means has been arrested and the loop has been cast around the needle below the barb, whereby the loop will be snugged under the barb for each stitch. -

2. In a sewing machine, embodying loop stitch forming means including a barbed needle, the combination of a rotatable thread supplying reel, positive reel braking means and periodically acting controlling mechanism therefor, and automatic, periodically actuated tension varying means, the periodic actions of the braking means and tension means cooperating to snug the thread under the needle barb in the formation of each stitch.

3. In a sewing machine, embodying loop stitch forming means including a barbed needle, the combination of a rotatable thread supplying reel, positive reel stopping means, including a ratchet and pawl, and periodically acting controlling mechanism therefor, and automatic, periodically actuated tension varying means, the periodic actions of the braking means and tension means cooperating to snug the thread under the needle barb in the formation of each stitch. 110 115

4. In a sewing machine, embodying loop stitch forming means including a barbed needle, the combination of a rotatable thread supplying reel, positive reel braking means and periodically acting cam governed controlling mechanism therefor, and automatic, periodically actuated cam governed tension varying means, the periodic actions of the braking means and tension means cooperating to snug the thread under the needle barb in the formation of each stitch. 120 125

JOSEPH A. GROEBLI
